United States Patent Office

Des. 196,184
Patented Sept. 3, 1963

196,184

SOUNDING TOY

Florindo F. Renzi, Leominster, Mass., assignor to A. J. Renzi Plastic Corporation, Leominster, Mass., a corporation of Massachusetts

Filed Aug. 13, 1962, Ser. No. 71,337

Term of patent 14 years

(Cl. D34—15)

The single FIGURE is a perspective view of a sounding toy embodying my new design.

The side of the article not shown is the substantial mirror image of the side shown.

I claim:

The ornamental design for a sounding toy, as shown and described.
